TRAY CLOSURE OR THE LIKE

James B. Swett, Barrington, R.I., assignor to Dart Industries Inc., Los Angeles, Calif.

Filed Nov. 2, 1971, Ser. No. 195,068

Term of patent 14 years

Int. Cl. D7—01

U.S. Cl. D7—40

FIG. 1 is a top plan view of a tray closure or the like showing my new design;

FIG. 2 is a bottom plan view thereof;

FIG. 3 is a front elevational view thereof; and

FIG. 4 is a side elevational view thereof.

I claim:

The ornamental design for a tray closure or the like, substantially as shown.
